(57) **CLAIM**

The ornamental design for a portable electronic gaming device, as shown and described.

DESCRIPTION

FIG. 1 illustrates a front and top perspective view of a portable electronic gaming device shown in an open position;

FIG. 2 illustrates a front and top perspective view of a portable electronic gaming device shown in an alternate position;

FIG. 3 illustrates a front and top perspective view of a portable electronic gaming device shown in a closed position;

FIG. 4 illustrates a rear and top perspective view of a portable electronic gaming device shown in an open position;

FIG. 5 illustrates a rear and top perspective view of a portable electronic gaming device shown in a closed position;

FIG. 6 illustrates a rear and bottom perspective view of a portable electronic gaming device shown in an open position; and,

FIG. 7 illustrates a rear and bottom perspective view of a portable electronic gaming device shown in a closed position.

The drawings FIGS. 2, 4 and 6 are drawn in reduced scale.
